UNITED STATES PATENT OFFICE.

JEREAD N. HYKE, OF SHERMAN, NEW YORK.

AUTOMATIC RAILROAD-CROSSING-GATE MECHANISM.

SPECIFICATION forming part of Letters Patent No. 722,845, dated March 17, 1903.

Application filed September 16, 1902. Serial No. 123,562 (No model.)

To all whom it may concern:

Be it known that I, JEREAD N. HYKE, a citizen of the United States, residing at Sherman, in the county of Chautauqua and State of New York, have invented certain new and useful Improvements in Automatic Railroad-Crossing-Gate Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to automatic railroad-crossing gates, and has for its object the construction and arrangement of a safety-gate mechanism so that the wheels of a train as it approaches a crossing from either direction will engage mechanism operating to automatically close the safety-gates.

The features of my invention are herein-after described, and set forth in the claims, and illustrated in the accompanying drawings, in which—

Figure 1 is a top or plan view of a section of railroad-track and a crossing embodying my invention. Fig. 2 is a side view in elevation of the same.

In the drawings, A is a section of a railroad-track, and a a' the rails thereof, of usual construction.

B B' are gate-posts at each side thereof and of a crossing, and C C', &c., are gates pivoted upon the gate-posts B B', &c., in the usual manner.

Under the posts B B' and extending across under the track A to the opposite parts there are mounted shafts D D', and on the ends of said shafts there are cranks d d', from which links E E' extend to and are pivoted to the rear ends c c' of the gates C C', so that the oscillation of the shafts D D' in one direction will close the gates C C' and in the other direction will open them.

At each side of the crossing at any desired distance therefrom I pivot on the outside of the rails a bars F F' in close proximity to the outside of the rail and with their outer ends

f pivoted somewhat below the top of the rail a, while their inner ends f' f' meet and rest upon a vertically-moving post H, provided with a spring I, which normally supports

the inner ends of the bars F F' some distance above the top of the rail a, so that the tread of the car-wheels as they pass over the bars F F' from either direction will gradually depress them as it moves from their outer to their inner ends, and as the wheel passes from their inner to their outer ends the bars F F' will gradually return to their normal position. The support H rests upon and is sustained by a spring I and is provided with a rack-gear h, which engages a gear-wheel J, mounted on a shaft K. This shaft K is provided with a crank k. The shaft D is provided with arms d² and d³ and the shaft D' with an arm d², and from the cranks K links L extend to studs on the outer ends of the arms d², and the inner ends of the links L, which engage the arms d², are provided with slots l, as and for the purpose hereinafter set forth. From the stud on the arm d² on the shaft D' a link M extends to a stud on the arm d³ on the shaft D, so that the shafts D and D' will oscillate in unison.

It will be observed that the operating mechanism herein described is alike in construction and operation at both sides of the crossing. Hence the description above given sufficiently describes the same.

In operation when the wheels of a train coming toward the crossing from either direction run upon the bars F F' the bars are depressed at their inner ends, which serves to depress the post H, which in turn rotates the shaft K and swings the crank k around in the direction of the arrow, which draws the link L back and oscillates through the link M both of the shafts D D' and operates therethrough to close the gates C C'. The slot l in the other link L allows the shafts to oscillate without moving the actuating mechanism at the other side of the crossing. After the train passes the crossing it engages the actuating mechanism at the opposite side of the crossing, which operates to again close the gates until the rear end of the train passes off of the same, when the weights on the ends c c' on the gates C C' operate to automatically open them.

I have thus shown and described convenient mechanism for utilizing my invention.

What I claim as new, and desire to secure by Letters Patent of the United States, is—

1. The combination in an automatic rail-

road-crossing-gate mechanism, of gates pivot-
ed to posts at opposite sides of the crossing,
gate-operating shafts extending across and
under the railroad-track from one gate-post
5 to another, cranks on the ends of said shafts,
links connecting the cranks with the gates,
arms on said shafts, a link connecting the
arms on said shafts at opposite sides of the
shafts, bars along the railroad-rail at each
10 side of the crossing so arranged that the tread
of the car-wheel will engage and gradually
depress them, vertically-movable posts actuated
by said depressible bars, crank mechanism actuated
thereby, and links having
15 slots in one of the ends thereof connecting
said crank mechanism with the arms on the
gate-operating shafts, substantially as and for
the purpose set forth.

2. The combination in an automatic rail-
road-crossing-gate mechanism of posts on op-
posite sides of the railroad and crossing, ver-
tically-moving gates pivoted on said posts,
shafts at each side of the crossing extending
from the bases of the posts across the rail-
25 road-track, cranks on the ends of said shafts,
links connecting said cranks with the rear

portions of said gates, arms on said shafts,
and links connecting said arms so that they
will oscillate in unison, bars along one rail
of the railroad-track pivoted at their outer 30
ends slightly below the top of the rail and
meeting at their inner ends, a yielding sup-
port under their inner ends normally sup-
porting them above the level of the top of the
rail so that as the tread of the wheels of a 35
train moves over the track from their outer
to their inner ends it will engage and gradu-
ally depress them, crank mechanism oper-
ated by said yielding support, and links hav-
ing their inner ends slotted, connecting said 40
cranks with the arms on said shaft, whereby
the mechanism at either side of the crossing
will operate the gates without operating the
mechanism at the other side, substantially as
and for the purpose set forth.

45 In testimony whereof I affix my signature
in presence of two witnesses.

JEREAD N. HYKE.
